CLAIM

The ornamental design for bird carrier, as shown and described.

DESCRIPTION

FIG. 1 is a front perspective view of my design for a bird carrier;

FIG. 2 is a front view of the bird carrier of FIG. 1;

FIG. 3 is a right side view of the bird carrier of FIG. 1, where the left side is a mirror image of the right;

FIG. 4 is a back view of the bird carrier of FIG. 1;

FIG. 5 is a top view of the bird carrier of FIG. 1;

FIG. 6 is a bottom view of the bird carrier of FIG. 1; and, FIG. 7 is a view of the interior of the bird carrier of FIG. 1 in its collapsible form.

The broken lines are for illustrative purposes only and form no part of the claimed design.
